UNITED STATES PATENT OFFICE.

GEORGE R. WEST, OF WILKINSBURG, PENNSYLVANIA.

DESIGN FOR A PLATE.

SPECIFICATION forming part of Design No. 36,538, dated September 8, 1903.

Application filed July 10, 1903. Serial No. 165,033. Term of patent 3½ years.

To all whom it may concern:

Be it known that I, GEORGE R. WEST, a citizen of the United States, residing at Wilkinsburg, in the county of Allegheny and State of Pennsylvania, have invented a new, original, and ornamental Design for a Plate, of which the following is a specification.

My design is shown in the accompanying drawing, which forms part of this specification.

In the drawing the plate of my design is shown in plan.

What I claim as new, and desire to secure by Letters Patent, is—

The ornamental design for a plate, as herein shown.

In testimony whereof I have hereunto set my hand.

GEORGE R. WEST.
